C. U. TYRRELL.
FOLDABLE PARACHUTE TOY.
APPLICATION FILED MAY 22, 1919.

Jno. G. Elliott

ATTORNEY.

UNITED STATES PATENT OFFICE.

CLAUDE U. TYRRELL, OF CHICAGO, ILLINOIS.

FOLDABLE-PARACHUTE TOY.

1,359,207.

Specification of Letters Patent. Patented Nov. 16, 1920.

Application filed May 22, 1919. Serial No. 298,860.

To all whom it may concern:

Be it known that I, CLAUDE U. TYRRELL, a citizen of the United States, and a resident of Chicago, in the county of Cook and 5 State of Illinois, have invented certain new and useful Improvements in Foldable-Parachute Toys, of which the following is a full, clear, and exact specification.

This invention relates to improvements in 10 foldable parachute toys, the flexibility of which has heretofore been so great that for their operation they must be carried to and dropped from a pre-determined height.

The object of my invention, broadly 15 stated, is to provide a foldable parachute toy adapted, while in its folded condition, to be projected from the ground upwardly into the air and thereby opened by the resistance of the air quickly following the expenditure 20 of the force propelling it upwardly.

More specifically stated, the object of my invention is to provide a foldable parachute with a stiffening means adapted to be manually forcibly projected from the 25 ground upwardly in the air and to open it independently of air pressure immediately following the expenditure of the force for its propulsion into the air.

A further object of my invention is a 30 foldable toy parachute so connected with a propelling means therefor that the force for its propulsion upwardly in the air is directed throughout the length of its folds and whereby the propelling force is utilized 35 to its fullest extent.

With these ends in view my invention finds embodiment in certain features of 40 novelty in the construction, combination, arrangement of parts by which the said objects and certain other objects are attained, all as hereinafter fully described with reference to the accompanying drawings, and more particularly pointed out in the appended claims.

45 In the drawings:

Figure 1 illustrates an inside elevation partly in section of a foldable parachute toy in which my invention finds its embodiment.

50 Fig. 2 is a similar view of the parachute in its folded position for forcibly projecting it upwardly into the air.

Fig. 3 is a detached view of one of the stiffening means therefor.

55 Fig. 4 is a side elevation of the coil

spring for releasing the parachute from its folded and locked position.

Fig. 5 is a bottom plan view of the weighted body or block to which the stiffening means is secured, and

Fig. 6 is a side elevation partly in section of said block.

Similar characters of reference indicate the same parts in the several figures of the drawings.

The hood member 7 of the parachute may be of any material suitable for its purpose, such for example as woven fabric of cotton or silk, and preferably the latter, but may be of bladder or thin sheet rubber 70 circular in form or of any other form by which it will assume the shape of an umbrella when exposed to currents of air directed against its under side.

Secured at intervals of each other are the 75 ends of cords 8 passing through eyes 9 in flexible metallic rods or wires 10, and of which there may be as many as there are cords 8, but as shown in the drawings there are but three equally distant apart at their 80 upper ends, which stiffening wires or rods are curved inwardly and converge until their ends 11 are brought and are preferably soldered together, and are adapted to be projected into an axial socket 12 in a block 13. 85

The block 13 has the form of an arrow-head provided at one side of its stem 14 adjacent the base of the arrow-head member with an upwardly inclined slot 15 adapted 90 to be engaged by a ring 16 secured to the top 90 of the parachute hood member when the parachute is folded, as shown in Fig. 2, and when the flexible stiffening wires 10 are brought close together, and the corners and cords of the hood member of the parachute 95 are in a position depending below these wires as indicated in Fig. 2.

The stem 14 of the block has the form of a hollow cylinder for inclosing a coil spring 17 surrounding the stiffening wires 10, one 100 end 18 of which spring is fixed to the stem by projecting it through a perforation 19 adjacent the outer end of the stem, the opposite end of the spring being seated against the base 20. The function of the spring 17 105 is to automatically release the ring 16 from the slot 15.

As soon as the force, for propelling the parachute upwardly into the air and the frictional resistance against the air of the hood 110

member of the parachute maintaining the ring in the slot, becomes less than that of the force of the spring, then the spring automatically operates to push the ring out 5 and free and clear of the slot, and whereupon the stiffening wires 10 will automatically separate to the position shown in Fig. 1, and the block, by reason of its greater weight, will thereby reverse its position and 10 descend by gravity.

As a means for projecting the parachute upwardly through the air, the block is provided in its side opposite the slot 15 with a notch 21, the direction of which is reversed with reference to the slot 15, the groove or notch 21 being adapted to be engaged by a ring 22 secured to a rubber strap 23, which is adapted to produce the force 15 for the propulsion of the parachute.

20 In operation, the parachute, in the folded position shown in Fig. 2, is so held by clasping it toward its lower end, for example with the left hand, then taking hold of the free end of the rubber strap with the right hand, and then pulling with the left hand away from the right hand until the rubber strap is fully stretched, followed by releasing the parachute from the left hand. By 25 means of the force so applied, the parachute 30 may be propelled upwardly through the air to a considerable distance limited only to the stiffness of the rubber strap and the strength of the operator.

In this connection it should be said that it 35 has been found in practice that a child of six or seven years or upward is able to project the aeroplane to a height of from 100 to 200 or more feet, and that the parachute will always fully open out almost at the 40 instant it begins its descent, and as soon as its body portion is reversed and the arrow head begins its descent.

In operation the parachute is folded against the resistance of the stiffening wires 45 and the ring is engaged with the notch in the block or arrow head as may be. The ring, following its engagement with the

notch, is projected between the lower free end of the spring and the block, so that when the resistance of the air due to the 50 force propelling the parachute upwardly into the air is expended, the spring will then operate to immediately force the ring from the notch and thereby permit the parachute to open concurrently with the commencement 55 of the downward movement of the block.

Having thus described my invention, what I claim and desire to secure by Letters Patent is:

1. A foldable parachute toy comprising a foldable hood member provided with a ring secured to the foldable member, a block suspended from said foldable member and having a notch therein adapted to be engaged 60 by said ring, and a spring adapted for disconnecting the ring from the notch after the propelling force is overcome by the air.

2. A foldable parachute toy comprising a hood member, a ring secured to the top of 70 said member, a block suspended from the foldable member and having a notch therein adapted to be engaged by the ring, and a spring inclosed by said block adapted to automatically disconnect the ring from the 75 notch at substantially the limit of the upward movement of the parachute.

3. A foldable parachute toy comprising a fabric hood member, fibrous cords attached thereto, a block member, flexible wires normally straight rigidly secured to said block and connected at their opposite end with said cords whereby when said hood is distended, said wires are curved outwardly from the block by the force of the pressure 85 of air distending the hood substantially as and for the purposes described.

In witness whereof, I have hereunto set my hand and affixed my seal, this 20th day of May A. D. 1919.

CLAUDE U. TYRRELL. [L. S.]

Witnesses:

MABEL RATZ,
JNO. G. ELLIOTT.
